UNITED STATES PATENT OFFICE.

EGBERT H. GOLD, OF CHICAGO, ILLINOIS.

CAR-HEATING SYSTEM.

1,077,525.

Specification of Letters Patent.

Patented Nov. 4, 1913.

Application filed April 15, 1912. Serial No. 690,750.

To all whom it may concern:

Be it known that I, EGBERT H. GOLD, a citizen of the United States, residing at Chicago, in the county of Cook and State of Illinois, have invented certain new and useful Improvements in Car-Heating Systems, of which the following is a specification.

My invention relates to car heating systems and particularly to steam heating systems suitable for heating railway cars.

One of the objects of the invention is to provide a system that may be successfully employed for heating railway cars under the conditions there prevalent in which the supply of medium to the radiating surfaces can be made to depend directly upon variations of temperature in the car through the instrumentality of a thermostat located in the car.

Various car heating systems have been proposed having for their objects automatic regulation by means of a thermostat located in the car, but for various reasons none of these proposed systems have, so far as I am aware, successfully overcome the difficulties arising from conditions peculiar to railway car heating.

Another object of the invention is to provide a steam heating system in which two or more radiating units are used to heat substantially the same region; the supply of steam to one of which units is controlled by a thermostat located in the car, so as to be responsive directly to temperature conditions in the car, while the other, which is preferably so arranged that it may be used or not as occasion demands, is maintained, when in use, full of steam at a constant pressure.

A further object of the invention is to improve upon the vapor or atmospheric pressure system of car heating by providing, in addition to the automatic control which prevents the steam in the radiator from appreciably exceeding atmospheric pressure, an automatic control which is dependent directly upon the temperature of the car whereby, if the maintenance of the desired temperature requires it, the amount of steam may be so reduced as to be less than sufficient to keep the radiator filled with steam, thus making it possible to obtain a closer regulation of temperature than is possible with the vapor or atmospheric pressure systems now in use.

A further and specific object of the in-

vention is to improve upon the multiple regulation heating systems shown in my patents numbered 987,565, 987,567, 987,568 and 987,569, all granted to me on the 21st day of March, 1911, and particularly to improve upon the system of regulation shown in the latter patent, the improvement being in the direction of a closer and more accurate regulation of the temperature maintained in the car.

The invention is illustrated, in a preferred embodiment, in the accompanying drawings, wherein—

Figure 1 is a fragmentary view, in perspective, showing the system applied to a railway car; Fig. 2, a sectional plan view of the shut-off valves for the radiating units; Fig. 3, a diagrammatic view of the thermostatically operated motor employed for operating one of the shut-off valves; Fig. 4, a vertical section taken on line 4—4 of Fig. 2, looking in the direction of the arrows, Fig. 5, a vertical section of the vapor regulator, and Fig. 6, a view similar to Fig. 1 showing a modification.

Like characters of reference designate like parts in the several figures of the drawings.

Referring to the drawings, A designates the floor of the car, B the steam train pipe located under the car and ordinarily supplied with steam from the locomotive boiler, C the vapor regulator, D the constant temperature radiating unit, E the variable temperature radiating unit, F and F' the shut-off valves for the radiating units D and E, respectively, G the motor for operating the shut-off valve F' and H the thermostat for actuating motor G, this thermostat being located within the car.

The radiating units D and E are arranged so that they heat substantially the same region, that is to say, the same portion of the car, and may therefore be considered as constituting a single radiator, one unit being intended to supplement the work of the other. Preferably the units are supplied with steam through a common supply pipe 10, 11 and discharge through a common discharge pipe 12. Each radiating unit has its separate cut-off valve and these valves F, F' are preferably so constructed and arranged that when both radiating units are under steam the course of the steam is through the units in succession. The purpose of this is to avoid short cir-

cuiting. By this arrangement a single vapor regulator or reducing valve may be employed for both units. This reducing valve or vapor regulator may be of any suitable character. I have shown in the drawings a well known vapor regulator interposed between the sections 10 and 11 of the common supply pipe.

Referring particularly to Fig. 5, 13 designates a casing which is divided into a high pressure chamber 14, to which leads pipe 10, and a low pressure chamber 15 from which leads the pipe 11. The port 16 between chambers 14 and 15 is controlled by a valve 17, the stem of which, 18, is connected with a bell crank 19 pivoted on a web 20. A thermostatic member 21 located in the outlet or thermostat chamber 22 supports a rod 23 pivoted to the other arm of the bell crank 19. The discharge pipe 12 leads to the thermostat chamber 22.

The operation of the vapor regulator above described is as follows: High pressure steam from train pipe B enters chamber 14 and passing the valve 17 goes through chamber 15 and thence into the low pressure section 11 of the radiator supply pipe. With one or both of the radiating units D and E open the steam passes from pipe 11 through said radiating unit or units and when the same have been filled with steam the excess escapes through the outlet pipe 12 and coming in contact with thermostat 21 causes the valve 17 to close or throttle the port 16, thus shutting off or diminishing further inflow into the radiating system. It will be understood that with the heating system in operation this action is ordinarily a balanced action, the valve 17 standing in such a position as to admit enough steam from the high pressure source to take care of the radiation loss and maintain the steam in the pipe 11 at atmospheric pressure or substantially atmospheric pressure.

45 The radiating unit or coil D, when used, is intended to be kept filled with steam at atmospheric pressure, the vapor regulator C serving to produce this result. The temperature of the medium in D will, therefore, 50 be a constant temperature regardless of the temperature of the atmosphere in the car. The flow of the heating medium from the common supply pipe 11 to the radiating unit or coil E is designed to be controlled in direct response to temperature conditions in the car so that the temperature of the medium in this coil will not be constant but will vary automatically in accordance with the requirements for heat in the car. In the 55 preferred arrangement shown it will never exceed the temperature of steam at atmospheric pressure. By the term "medium" in this connection I intend the contents of the coil whether it be steam, vapor, air, or 60 water of condensation.

The construction and arrangement of the shut-off valves is best shown in Figs. 2 and 4. Valves F and F' are exactly alike so that but one need be described. The device consists of a casing divided by the webs 24 into four chambers 25, 26, 27 and 28. Arranged between the webs 24 is a valve consisting of the upper and lower disks 29 and 30 and connecting web 31. The valve has a stem 32 extending through the bonnet 33 and provided with the operating handle 34. A spring 35 bears against the upper disk 29. The lower disk 30 has a waste port 36 which registers with the waste port 37 in the bottom of the casing. When the valve is turned to the position shown in Fig. 2 so as to close the radiating coil D the waste port 36 communicates with a drip pipe 38 (Fig. 1) extending through the floor of the car. Pipe 11 leads into the chamber 25 of valve F. The inlet end and outlet ends of the coil D communicate, respectively, with chambers 26 and 27. Chamber 28 of valve F communicates by means of a short pipe 39 with the chamber 25 of valve F'. The inlet and outlet ends of coil E communicate with chambers 26 and 27, respectively, of valve F'. The discharge pipe 12 leads from chamber 28 of valve F'. With the parts in the position shown in Fig. 2 the steam from pipe 11 passes directly into the coil E. With the web 31 of valve F at right angles to the position shown in the drawings the steam passes first through coil D and then through coil E. If the web 31 of valve F' is turned at right angles to the position shown in the drawings the coil E is cut out. It will be seen that if desired both coils can be cut out, in which case the steam from pipe 11 passes directly to the thermostat 21 of the vapor regulator.

The thermostat H is located in the car. It is shown as consisting of the usual bar 40 made up of metals having unequal coefficients of expansion, which bar carries a contact 41 adapted to be brought against a contact 42 when the temperature in the car exceeds the desired maximum. The contacts 41, 42 are arranged in circuit with a battery 43 and with the solenoid 44 of the motor G. The core 45 of the solenoid carries a stem 46 which is connected with the handle 34 of the valve F'. A spring 47 is interposed between the guide 48 for the stem and a collar 49 on said stem and serves to return the handle 34 to its original position when the battery circuit is broken by separation of contacts 41, 42, this occurring when the temperature of the car is reduced to such point as requires the reopening of the coil E.

It will be understood that any suitable form of thermostat could be used. The invention is not limited to the electrically operated thermostat shown and described. Likewise any suitable form of vapor reg-

ulator may be used in place of the one shown, and also shut-off valves or equivalent devices of any suitable construction in place of the four-way valves shown without departure from my invention.

- The system herein shown and described may be operated as follows: If the weather is moderate coil E alone will be used. The vapor regulator C will, of course, prevent 10 the steam in the coil from exceeding atmospheric pressure. However, the mean temperature of the medium in the coil will be reduced below the temperature of steam at atmospheric pressure if such reduction is 15 necessary in order to keep the temperature of the car down to the right point. If the temperature in the car exceeds this maximum the radiator E is shut-off from the steam supply. It will thus remain closed at 20 such intervals as is necessary to keep the car at the right temperature.

Various car heating systems have been proposed in which the object was to control the radiator supply automatically in response to temperature changes in the car. These systems have one and all failed so far as I am aware. In some cases the failure has been due to the fact that the effort was made to operate the thermostatically controlled valves against train pipe pressure. Train pipe pressures are often too high to make this feasible and moreover, they are subject to such a wide range of variation as to make any such system of regulation entirely unreliable. Furthermore, the proposed systems ordinarily have operated on the principle of throttling the steam. The result of this was that freeze ups occurred whenever the throttling diminished the 35 flow to a certain point. The system of my invention operates in an entirely different manner and thereby avoids these difficulties. The thermostatically controlled radiator valve F' works against a constant pressure 40 which, in the preferred form of the invention, is but little, if any, above the pressure of the atmosphere. Furthermore, the valve is a shut-off valve and not a throttle valve. When the radiating coil is cut out the water 45 of condensation finds free vent through the waste ports 36, 37. The vapor regulator C at such time is kept hot by steam which flows directly from pipe 11 to pipe 12 and thence to the thermostat chamber 22. Hence 50 port 16 is at such times closely throttled so that the pressure in the supply pipe 11 remains low. If shutting off the radiator involved cutting out the thermostat the pressure would rise in the supply pipe 11 to 55 such an extent that the radiator valve F' could not fail but leak, which would of course defeat the purposed thermostatic regulation. By making the thermostatically controlled valve of the rotary type, 60 which is feasible because of the low pres-

sure handled, instead of having the valve screw up and down as is usual, the operation of the valve by the thermostatically actuated motor is simplified and made more certain. When the coil E alone is used any amount 70 of heat will be delivered to the car ranging from nothing up to full capacity of the coil when kept filled with steam at atmospheric pressure:

If it be found that the coil E is insufficient 75 to properly heat the car the attendant will open up coil D. The inflow of steam to coil E is temporarily shut-off, that is, until coil D has become filled with steam. By the time this has occurred the temperature of the car 80 may have been raised to the desired point. If not, as soon as that point is reached or exceeded the coil E will be cut out by the operation of the thermostatic control. Thereafter the coil E will simply supplement the operation of coil D delivering such 85 amount of heat to the car as is necessary to keep up the desired temperature.

In Fig. 6 I have shown a modification in 90 which a separate vapor regulator is provided for each of the units or coils. In other respects the system is just like that above described. Referring to this figure, the steam enters the radiating unit D through a pipe 43, 44 in which is interposed the vapor regulator C'. The discharge from the radiating unit D goes directly to the vapor regulator C' through pipe 45. Steam from the train pipe is admitted to 95 radiating unit E by pipe 46, 47, in which pipe is interposed a second vapor regulator C''. A pipe 48 leads from the four-way valve F' to the thermostat chamber of the second controller.

While I have described my invention as 100 embodied in certain preferred constructions and arrangements, it will be obvious that modifications might be made without departure from the invention. Therefore I do not limit myself to the particulars shown 105 and described except so far as the same are made limitations in certain of the claims; my object being to claim, both broadly and narrowly, whatever patentable novelty my 110 heating system may possess in view of the 115 state of the art.

I claim:

1. In a heating system for railway cars, the combination with a radiator comprising two radiating units arranged so as to heat 120 the same region, of controlling means for one of said units which maintains the medium therein at a relatively constant temperature, and controlling means for the other unit which automatically varies the 125 temperature of the medium in said unit.
2. In a heating system for railway cars, the combination with a radiator comprising two radiating units arranged so as to heat 130 the same region, of controlling means for

one of said units which maintains the medium therein at a relatively constant temperature, and controlling means responsive directly to temperature conditions in the 5 car which automatically varies the temperature of the medium in the other radiating unit.

3. In a heating system for railway cars, the combination with a radiator comprising 10 two radiating units arranged so as to heat the same region, of controlling means for one of said units automatically responsive to thermostatic conditions in the medium out-flowing from said unit, and controlling 15 means for the other unit automatically responsive directly to temperature conditions in the car.

4. In a heating system for railway cars, the combination with a radiator comprising 20 two radiating units arranged so as to heat the same region, of means for maintaining one of said units filled with steam at a constant pressure, and means responsive directly to temperature conditions in the car 25 for proportionately varying the amount of steam admitted to the other unit.

5. In a heating system for railway cars, the combination with a radiator comprising two radiating units arranged so as to heat 30 the same region, of means for maintaining one of said units filled with steam at atmospheric pressure, and means responsive directly to temperature conditions in the car for proportionately varying the amount of 35 steam admitted to the other radiating unit.

6. In a heating system for railway cars, the combination with a radiator comprising two radiating units arranged so as to heat the same region, of means for maintaining 40 the medium in said units at atmospheric pressure, and means for automatically varying the supply of steam to one of said units so as to vary its heating capacity from substantially nothing to its maximum heating 45 capacity when filled with steam at atmospheric pressure.

7. In a heating system for railway cars, the combination with a radiator comprising two radiating units arranged so as to heat 50 the same region, of means for maintaining the medium in said units at atmospheric pressure, and means directly responsive to temperature conditions in the car for automatically varying the supply of steam to one of said units so as to vary its heating capacity from substantially nothing to its maximum heating capacity when filled with steam at atmospheric pressure.

8. In a heating system for railway cars, 60 the combination with a radiator comprising two radiating units, a common supply pipe and a common outlet pipe for said units, an automatic controller arranged to maintain steam at a constant pressure in the common supply pipe, one of said radiating units be-

ing connected with the common supply pipe so that it may be continuously supplied with steam therefrom, and means directly responsive to temperature conditions in the car for automatically varying the inflow of steam 70 to the other of said units.

9. In a heating system for railway cars, the combination with a radiator comprising two radiating units, a common supply pipe and a common outlet pipe for said units, an 75 automatic controller responsive to thermostatic conditions in the common outlet for maintaining steam at substantially atmospheric pressure in the common supply pipe and one of said units, and means directly responsive to temperature conditions in the car for varying the inflow of steam to the 80 other of said units.

10. In a heating system for railway cars, the combination with a radiator comprising 85 two radiating units, a common supply pipe and a common outlet pipe for said units, an automatic controller arranged to maintain steam at a constant pressure in the common supply pipe, means directly responsive to 90 temperature conditions in the car for varying the inflow of steam to only one of said units, and a valve for shutting off the inflow from the common supply pipe to the other of said units.

11. In a heating system for railway cars, the combination with a radiator comprising two radiating units, a common supply pipe and a common outlet pipe for said units, an automatic controller arranged to maintain steam at a constant pressure in the common supply pipe, valves adapted to shut off the steam from said units separately, one of said 100 valves being manually operable and automatically operated means for opening and closing the other of said valves.

12. In a heating system for railway cars, the combination with a radiator comprising two radiating units, a common supply pipe and a common outlet pipe for said units, an 110 automatic controller arranged to maintain steam at a constant pressure in the common supply pipe, valves adapted to shut off steam from said units separately, and means directly responsive to temperature conditions in the car for automatically opening and closing one of said valves.

13. In a heating system for railway cars, the combination with a radiator comprising two radiating units, a common supply pipe 120 and a common outlet pipe for said units, an automatic controller arranged to maintain steam at a constant pressure in the common supply pipe, valves for separately shutting off steam from said units which connect said units in series when both are receiving steam, one of said valves being manually operable, and automatically operated means for opening and closing the other of 125 said valves.

14. In a heating system for railway cars, the combination with a radiator comprising two radiating units, a common supply pipe and a common outlet pipe for said units, an automatic controller arranged to maintain steam at a constant pressure in the common supply pipe, two four-way valves connected with each other, the inlet and outlet ends of each unit being connected, in each case, with one of said valves, the common supply pipe leading to one of said valves and the common discharge pipe leading from the other, whereby steam may be directed into either of said units or through both of the units in series, and means responsive to temperature conditions in the car for operating one of said four-way valves to open and close one of said units.
15. In a heating system for railway cars, the combination with a source of steam at normally high but varying pressures, of a radiator comprising two radiating units arranged so as to heat the same region in the car, valves to govern the admission of steam to said heating units separately, one of said valves being manually operable, a thermostat arranged within the car to operate the other of said valves, and means actuated automatically to prevent the steam in the unit or units in service from exceeding a definite pressure lower than the normal range of pressures in the source of supply.
16. In a heating system for railway cars, the combination with a source of steam at normally high but varying pressures, of a radiator comprising two radiating units ar-

ranged so as to heat the same region in the car, valves to govern the admission of steam to said heating units separately, one of said valves being manually operable, a thermostat arranged within the car to operate the other of said valves, and means actuated automatically to prevent the steam in the unit or units in service from substantially exceeding atmospheric pressure.

17. In a heating system for railway cars, the combination of a radiator comprising a plurality of units arranged to heat the same compartment, means for controlling the supply of the heating medium to a portion of said units so as to maintain therein a substantially constant temperature and automatic means for controlling the supply of the heating medium to other of said units so as to vary the heating effect of said radiator.

18. In a heating system for railway cars, the combination of a radiator comprising a plurality of radiating units arranged to heat the same compartment, of heat-controlling means for a portion of said units automatically responsive to thermostatic conditions in the medium out-flowing from said radiator, and heat-controlling means for other of said units automatically responsive directly to variations in the temperature conditions in said compartment.
